US00D605165S

(12) **United States Design Patent**
Sheba et al.

(10) **Patent No.:** US D605,165 S
(45) **Date of Patent:** ** Dec. 1, 2009

(54) **MEDIA PLAYER**

(75) Inventors: **Yaron Sheba**, Mountain View, CA (US);
Philip L. Ly, San Jose, CA (US)

(73) Assignee: **SanDisk Corporation**, Milpitas, CA
(US)

(**) Term: **14 Years**

(21) Appl. No.: **29/337,735**

(22) Filed: **May 28, 2009**

(51) **LOC (9) Cl.** **14-03**

(52) **U.S. Cl.** **D14/203.7; D14/496; D14/293.3**

(58) **Field of Classification Search** ..... **D14/496, D14/401, 435, 474, 483, 217, 137, 138, 160, D14/168, 356, 203.1–203.8, 507; 345/156, 345/169, 173–179, 905; 715/727–729, 864; 710/1, 5, 8; 713/1, 600; 455/1.1, 1.7, 73, 455/344–347, 93, 95, 3.01–3.06, 550.1, 573.1; 370/342–344; 369/1, 2, 6–12; 463/43–47; 273/148 B**

CLAIM

The ornamental design for a media player, substantially as shown and described.

DESCRIPTION

FIG. 1 is a perspective view of a media player showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines, which define the bounds of the claimed design, form no part thereof. The broken lines showing environment are for illustrative purposes only and form no part of the claimed design.

1 Claim, 5 Drawing Sheets
